UNITED STATES PATENT OFFICE.

WILLIAM E. OAKLEY, OF ASTORIA, NEW YORK, ASSIGNOR TO OAKLEY FOUNDRY AND ENGINEERING COMPANY, OF ASTORIA, NEW YORK, A CORPORATION OF NEW YORK.

APPARATUS FOR BURNING LIQUID FUEL.

1,103,535.

Specification of Letters Patent. Patented July 14, 1914.

Application filed April 5, 1911. Serial No. 619,074.

To all whom it may concern:

Be it known that I, WILLIAM E. OAKLEY, a citizen of the United States, residing at Astoria, in the county of Queens and State 5 of New York, have invented a new and useful Improvement in Apparatus for Burning Liquid Fuel, of which the following is a specification.

My invention relates to improvements in 10 an apparatus for burning liquid fuel, in which the fuel is burned in open pans over which currents of air pass, carrying flame and heated air wherever it is desired to apply the heat generated by the burning liquid 15 fuel. In the present instance the pans are shown in proper position to allow the currents of heated air to be conducted through the flues of a boiler, or into the heating chamber of a furnace for melting metal.

The objects of my invention are to provide 20 means for determining the amount of heat generated by the burner by automatically controlling the supply of liquid fuel to the pans and the supply of air above the 25 pans, and thereby regulating the relative supply of fuel and oxygen to the burner, thereby controlling the combustion of liquid fuel and the heat generated by the burner.

I attain these objects by the mechanism, 30 illustrated in the accompanying drawing, showing a vertical sectional view of a portion of a furnace equipped with my improved apparatus for burning liquid fuel, and showing, also in section, the apparatus 35 for automatically controlling the flow of liquid fuel to the burner.

In the accompanying drawing, 1 is the front wall of a combustion chamber 2, which may communicate with another chamber, 40 not shown, to which it is desired to apply heat. Fuel pans 6, 8 and 10 are provided in the passages 3 of the wall 1, the pans being supplied with liquid fuel by a pipe 5 leading from a source of liquid fuel, not 45 shown, and delivering the fuel into the top-most pan 6. From this pan 6 the fuel is delivered by an overflow pipe 7 to a second pan 8, which communicates by an overflow pipe 9 with the lowest pan 10. Above the 50 pans is a passage 11 designed solely for the admission of air to the combustion chamber 2. Each of the passages 3 and the passage 11 are provided with a hinged door 12 by which the amount of air entering through 55 each passage may be determined. The open-

ing and closing of these hinged doors is automatically regulated by the same apparatus which controls the supply of liquid fuel to the pans, as will be explained hereafter. A tank 13 is provided, connected at the bottom with the bottom of the lowest pan 10, so that the level of the liquid fuel in the tank 13 and in the lowest pan 10 will always be the same. Supported by the liquid fuel in the tank 13 is a float 14, preferably hollow, and attached at its top to a lever 15 pivoted at 16. Pivoted at 17 on the arm 18, attached to the side of the tank 13, is a second lever 19, one end 20 of which is connected with the lever 15 by the link 21 and 60 the other end 22 of which is connected by a rod 25 with the gate valve 23 in the liquid fuel supply pipe 5.

Elevation of the float 14 by the liquid fuel in the tank 13 will raise the lever 15 and the 75 end 20 of the lever 19, thereby lowering the end 22 and closing the gate valve 23 in the liquid fuel supply pipe 5. In this manner the supply of liquid fuel through the pipe 5 is dependent upon the amount of liquid fuel 80 in the lowest fuel pan 10, the level of which is coincident with the level of the liquid fuel in the tank 13.

Variation in the displacement of fuel by the float 14 and, therefore, in the elevation of the float, is obtained in the following manner:—A counterbalance weight 24 is provided on the lever 19 on the other side of the pivot 17 from the float 14. This weight is adjustable toward and away from 85 the pivot 17, therefore increasing or diminishing, by the difference in leverage, its effect on the displacement of fuel by the float 14 and, therefore, its effect on the elevation of the float. This varies the level of 90 the liquid fuel in the tank 13 necessary to lift the float 14 sufficiently to raise the lever 15, lower the end 22 of the lever 19 and close the gate valve 23. The level in the tank 13 may be changed by adjusting the 95 weight 24 on the lever 19 to vary, as desired, the amount of fuel in the lowest pan 10 when the gate valve 23 closes. In the drawing the weight is shown in its position nearest to the pivot 17, in which position the 100 effect of the weight is such that the displacement of fuel by the float will be a maximum, the normal level of the fuel in the tank 13 and in the pan 10 will be highest, and the 105 amount of fuel necessary in the tank 13 and 110

pan 10 to close the valve 23 will be greatest. This amount of fuel is shown in the tank 13, so that in the drawing the gate is represented in its closed position. As the amount of fuel in the fuel pans is diminished by burning, the level in the lowest pan 10 and tank 13 is lowered and the float 14 sinks, thereby opening the gate valve 23 and again admitting liquid fuel to the burner. This regulation is extremely accurate as only a small variation in the level of the float 14 is necessary to open the gate valve 23 wide enough to control the fuel supply.

If the shutting of the valve 23 is desired before the level of the fuel in the pan 10 attains the height shown in the drawing, moving the weight 24 toward the end 22 of the lever 19 lessens the displacement of the float 14, thereby reducing the amount of liquid fuel necessary to close the valve and so lowering the normal level of fuel in the tank 13 and lowest pan 10. The length of the lever 19 beyond the pivot 17 is arranged so that if the weight 24 is in the position shown by dotted lines in the drawing on the end of the lever 19, the level of the fuel in the tank 13 is that of the lower of the two dotted lines connecting the tank 13 and pan 10, under which conditions there is no fuel in the pan 10. In this way I provide adjustable apparatus for automatically controlling the supply of liquid fuel to the fuel pans. The supply of oxygen to the combustion chamber I also automatically control by an apparatus which is manually adjustable for regulating the relative amounts of opening of the hinged doors 12, which apparatus is connected with the float 14 and operated simultaneously with the gate valve 23. This apparatus consists of a lever 26 pivoted at 27 above the hinged doors 12 of the burner, to which the end 28 of the lever 26 is connected by chains. The chain 29 connects the end 28 of the lever 26 with the door 12 for the passage 11, and the chain 30 forms the connection between the doors of the passages 3 and the end 28 of the lever. Hooks 31 are provided for the chains connecting the hinged doors of each of the passageways, thereby allowing the separate adjustment of each door to vary the amount of the opening for each passageway and the admission of air to the combustion chamber. By the adjustment of the chains 29 and 30 to vary their effective lengths, the time of opening of the doors connected to said chains as well as the amount of opening of said doors, can be varied. For example, by lengthening the chain 29 so that in the closed position of the door connected thereto a portion of the said chain lies slack, the opening of said door will be later than the opening of the doors connected to the chain 30, provided the said chain 30 does not lie

slack in the closed position of the doors. By this means the doors may be opened and closed either simultaneously or separately, as desired. The simultaneous adjustment of all the doors 12 is provided for by the hook 32 in the chain 33, connecting the end 34 of the lever 26 with the lever 19 through which the doors are operated by the float 14. The supply of oxygen by the admission of air through the hinged doors 12, and the supply of fuel by the supply of liquid fuel through the pipe 5 are, therefore, automatically controlled together by my apparatus by the elevation of the float 14 which is varied by the level of the fuel in the lowest pan 10.

The relative supply of fuel and oxygen is varied by adjusting the weight 24 on the lever 19 to change the amount of liquid fuel admitted to the fuel pans 4 and hence the amount of fuel supplied to the burner, or by varying the amount of opening of the doors 12 by adjusting the positions of the hooks 31 to change the amount of oxygen admitted to the combustion chamber.

I thus provide means for varying or regulating the supply of fuel to the combustion chamber and separate means for varying or regulating the supply of oxygen to the combustion chamber, these means being controlled and adjusted simultaneously by the float. The elevation of the float is automatically regulated by changes in the level of the fuel within the tank 13 and, inasmuch as this level is directly controlled by the level of the fuel in the pan 10, the level of the float is also directly controlled by the elevation of the fuel in this pan. The means which regulates the supply of oxygen to the combustion chamber is also manually adjustable to vary the relative supply of oxygen to each individual fuel pan. The means which regulates the supply of fuel to the fuel pan is automatically controlled by the float and, therefore, by changes in the level of the fuel in the fuel pan 10. The action of this automatic controlling means is also manually adjustable by changing the position of the weight 24.

I claim,

1. In an apparatus of the class described, the combination with a liquid fuel pan, and a passage for air above said fuel pan, of means responsive to changes in the level of fuel in said pan for controlling the supply of fuel to said pan and for controlling the flow of air through said passage.

2. In an apparatus of the class described, the combination with a liquid fuel pan and a passage for air above said fuel pan, of adjustable means for controlling the supply of fuel to said pan, said means being responsive to changes in the level of fuel in said pan, and means actuated by the fuel supply controlling means for opening and closing said passage.

35

40

45

50

55

3. In an apparatus of the class described, the combination with a liquid fuel pan and a passage for air above said fuel pan, of adjustable means for controlling the supply of

5 fuel to said pan, said means being responsive to changes in the level of fuel in said pan, and manually adjustable means actuated by the fuel supply controlling means for opening and closing said passage.

10 4. In an apparatus of the class described, the combination with a liquid fuel pan and a passage for air above said fuel pan, of a tank for liquid fuel in communication with said pan so that the level of fuel in both

15 tank and pan will be the same, a float in said tank, means for controlling the supply of fuel to said pan, means for controlling the flow of air through said passage, and means actuated by the float for operating the fuel

20 and air controlling means.

5. In an apparatus of the class described, a combustion chamber, an air passage leading thereto, means for opening and closing said air passage, a liquid fuel pan below

25 said passage, means for controlling the level of the fuel in said pan, and means actuated by said controlling means for operating said opening and closing means.

6. In an apparatus of the class described, 30 the combination with a liquid fuel pan, of an air passage separate from said fuel pan.

and means arranged to open and close said air passage, said means being controlled in accordance with the level of fuel in said fuel pan.

7. In an apparatus of the class described, the combination with a liquid fuel pan, of an air passage above said fuel pan, a second air passage separate from said fuel pan, separate means arranged to open and close 40 said air passages, said means being arranged to be operated simultaneously, and means controlled in accordance with the level of fuel in said fuel pan for actuating both of said opening and closing means.

8. In an apparatus of the class described, the combination with a liquid fuel pan, of a passage for air above said fuel pan and a second passage for air separate from said fuel pan, means for controlling the supply 50 of fuel to said pan, said means being also arranged to automatically open and close said passages either separately or simultaneously as desired, with the operation of said means determined in accordance with 55 the level of fuel in said fuel pan.

Dated this twenty ninth day of March 1911.

WILLIAM E. OAKLEY.
